UNITED STATES PATENT OFFICE.

WINFRED S. GRIFFITH, OF WORCESTER, MASSACHUSETTS, ASSIGNOR TO HEALD MACHINE COMPANY, OF WORCESTER, MASSACHUSETTS, A CORPORATION OF MASSACHUSETTS.

DESIGN FOR A MAGNETIC CHUCK.

47,038.

Specification for Design.

Patented Mar. 2, 1915.

Application filed April 13, 1914. Serial No. 831,647. Term of patent 7 years.

To all whom it may concern:

Be it known that I, WINFRED S. GRIFFITH, a citizen of the United States, residing at Worcester, in the county of Worcester and State of Massachusetts, have invented a new, original, and ornamental Design for a Magnetic Chuck, of which the following is a specification, reference being had to the accompanying drawing, forming part thereof.

The figure is a perspective view of a magnetic chuck showing my new design.

I claim:—

The ornamental design for a magnetic chuck as shown.

WINFRED S. GRIFFITH.
